UNITED STATES PATENT OFFICE.

HORATIO N. BUZZELL, OF PANA, ILLINOIS.

DRIER.

SPECIFICATION forming part of Letters Patent No. 242,267, dated May 31, 1881.

Application filed February 26, 1881. (No model.)

To all whom it may concern:

Be it known that I, HORATIO N. BUZZELL, a citizen of the United States, resident at Pana, in the county of Christian and State of Illinois, have invented certain new and useful Improvements in Driers; and I do hereby declare the following to be a full, clear, and exact description of the invention, such as will enable others skilled in the art to which it appertains to make and use the same, reference being had to the accompanying drawings, and to letters or figures of reference marked thereon, which form a part of this specification.

Figure 1 is a vertical central sectional view, and Fig. 2 is a horizontal sectional view taken on the line $x x$ in Fig. 1.

This invention relates to improvements in devices for drying fruit or other articles.

The invention consists in the construction hereinafter described, and particularly pointed out in the claim.

In the annexed drawings, A represents a receptacle, made round or octagonal, and of any material, brick being preferable, as it is a good absorbtion of heat.

B are furnaces in the bottom, having doors b and chimneys C. In the middle, at the bottom, is a step, D.

E is a shaft stepped in step D and running up through the drier and coming out at the roof. To this shaft are secured radial arms F in one or more series. On these arms are supported the shelves G, two or more in number; or the ends of the arms may be connected and short sections of gauze H laid thereon.

I are short tubes leading from the inside of the drier, at the top, to the chimneys.

K is the door.

Fruits, vegetables, or clothes, as the case may be, are placed on the shelves, the door 40 closed, and fire made in the furnaces. The shaft E is then revolved in any suitable manner, by belting or otherwise. As the heated air rises the articles are dried, the moisture leaves them, and, being whirled to the walls, 45 it rises and passes out through the tubes into the chimneys. In these tubes I valves may be placed for preventing too rapid escape of the heat or regulating its escape from the drier. A drier having two chambers, one above the 50 other and both above the furnace, has been provided with a hollow central rotating shaft, through which the products of combustion pass to the open air, spiral flanges upon the rotating shaft being relied upon to operate it. 55 This construction is, however, not claimed herein.

What I claim is—

In a drier, the receptacle A, provided with furnaces B, chimneys C C, and valved pipes I, 60 connecting the receptacle and chimneys, in combination with the central shaft, E, stepped in the step D, provided with the shelves G H, and adapted to be operated by external power applied to the shaft E above the roof of the 65 receptacle, substantially as and for the purposes set forth.

In testimony whereof I affix my signature in presence of two witnesses.

HORATIO N. BUZZELL.
